UNITED STATES PATENT OFFICE

BENJAMIN FISCHER, OF NEW YORK, N. Y.

CHILD'S SLEEPING GARMENT

Application filed March 2, 1932. Serial No. 596,344.

This invention relates to improvements in sleeping garments, and more particularly to children's sleeping garments.

The primary object of the invention resides in a sleeping garment for children or infants which consists of an upper garment section and a removable lower garment section which when assembled imparts the appearance of a one piece garment. This enables the ready removal of the lower garment section when wet or soiled by the child during sleep and the substitution of a fresh or clean lower garment section therefor.

Another feature of the invention is to provide a child's sleeping garment which is buttonable at the front rather than at the back, as is the present style to prevent the imprint of the buttons upon the wearer's body while lying on his or her back, and which is further provided with a drop flap on the lower garment section at the front thereof to facilitate the changing of a child's diapers without requiring the placing of the child on its stomach as is the present custom.

A further object of the invention is the provision of a child's sleeping garment which is comfortable, easy to apply and remove, attractive in appearance, and inexpensive of manufacture.

With these and other objects in view, the invention resides in the certain novel construction, combination and arrangement of parts, the essential features of which are hereinafter fully described, are particularly pointed out in the appended claims, and are illustrated in the accompanying drawing, in which:

Figure 1 is a front elevational view of my improved sleeping garment.

Figure 2 is a rear elevational view of the same.

Figure 3 is a fragmentary front elevational view of the lower section per se with the front drop flap partially turned down.

Figure 4 is a front elevational view of the upper garment section.

Referring to the drawing by reference characters, the numeral 10 designates my improved child's sleeping garment in its entirety which includes an upper garment sec-

tion 11 and a removable lower garment section 12.

The upper garment section 11 is buttonable at the front for the length thereof as at 12', and includes sleeves 13 and a neck 14. The front of the garment section 11 adjacent the lower edge thereof is provided with a series of buttons 15, the said section being short waisted so that the buttons 15 are disposed just above the waist of the wearer when the garment is in worn position.

The lower garment section 12 is made of the same material as the upper garment section 11 and includes legs 16 which are provided with feet 17. The front of the lower garment section 12 is provided with a drop flap 18 which is provided with button holes 19 adjacent the top edge thereof. These button holes correspond in numbers to the number of buttons 15 on the front lower edge of the upper garment section 11. Extending upwardly from the rear or seat portion of the lower garment section 12 is a back portion 20 having opposed side flaps 21 which are brought around to overlie opposite sides of the drop flaps 18 and which side flaps are provided with button hole openings 22 by which the said flaps may be buttoned to the end buttons of the row 15. The top edge of the back portion 20 is cut away as at 23 about the collar or neck 14 of the upper garment section 11, and which cut away portion provides shoulder straps or tabs 24, having button hole openings 25 therein. These tabs or straps are brought forwardly over the shoulders of the upper garment section 11 and are secured by buttons 26 carried by the upper garment section 11 at the shoulders thereof.

Assume that the garment is in the buttoned up position shown in Figure 1 of the drawing, and it is desired to apply the same to a wearer. The buttons 12' are unbuttoned together with the buttons 15 whereupon the legs and arms of the wearer may be inserted into the legs 16 of the lower garment section and sleeves 13 of the upper garment section and the parts again closed by rebuttoning the buttons 12' and 15. In the event that the lower garment section 12 should become wet or soiled by the child during sleep, the

same may readily be removed without disturbing the upper garment portion which due to its short waist is not likely to become soiled. To remove the lower garment section 12 it is only necessary to unbutton the buttons 26 and 15 whereupon a child lying on its back may be pulled free of the upper garment section 11. A fresh or clean lower garment section may be substituted therefor by merely inserting the legs of the child into the leg portions 16 of the lower garment section and sliding the rear portion 20 beneath the child and up and around the shoulders of the upper garment section 11. The straps 24 are buttoned to the buttons 26. The drop flap 18 is then brought up and buttoned to the buttons 15 as are the side flaps 21.

By reference to Figure 2 of the drawing it will be seen that the back section 20 is loose or full especially at the seat to provide ample comfort for the child that requires diapers. When it is necessary to change the diaper, the child may be laid on its back and the side flaps 21 unbuttoned together with the drop flap 18 and the leg portion 16 of the lower garment free of the legs of the wearer. After changing of the diaper the parts are rebuttoned and the changing accomplished without placing the child in an uncomfortable position upon its stomach. It will also be noted that no buttons appear on the back of the garment which in the present style of sleeping garment is objectionable due to the fact that the imprint of the button is often left upon the body of the child accustomed to sleeping on its back. Also, there are no buttons at the sides of the garment which might leave an imprint upon the body in the event that the child slept on its side.

While I have shown and described what I deem it be the most desirable embodiment of my invention, I wish it to be understood that such changes as come within the scope of the appended claims may be resorted to if desired.

Having thus described the invention, what I claim as new and desire to secure by Letters Patent is:—

- 50 1. A sleeping garment comprising an upper garment section buttonable down the front, a lower garment section buttonable to the lower front edge of said upper garment section, and a back section extending from the rear of said lower garment section and overlying the back of said upper garment section, and buttonable to the upper garment section at the shoulders thereof.
- 55 2. A sleeping garment comprising an upper garment section buttonable down the front, a lower garment section buttonable at the lower front edge of said upper garment section, and a back section extending from the rear of said lower garment section, and buttonable to the upper garment section at

the shoulders thereof, and side flaps extending from opposite sides of said back section and buttonable to the front of said upper garment section and overlying the front of said lower garment section at the sides thereof.

3. A sleeping garment comprising an upper garment section buttonable down the front thereof, a lower garment section having its front buttonable to the lower edge of the front of said upper garment section, a back portion extending from said lower garment section and loosely overlying the back of said upper garment section, and shoulder straps on said back portion extending forward over the shoulders of said upper garment section and buttonable thereto.

4. A garment comprising an upper garment section, a lower garment section detachably secured to the lower front edge of said upper garment section, a back section extending from the rear of said lower garment section and terminating in shoulder straps for detachable engagement with the shoulders of said upper garment section, and side flaps extending from opposite sides of said back section and detachably engageable with the front of said lower garment section and overlying the same at the end thereof.

In testimony whereof I affix my signature.

BENJAMIN FISCHER.
